UNITED STATES PATENT OFFICE.

WILLIS S. SHERMAN, OF MILWAUKEE, WISCONSIN.

TONGUE-AND-GROOVE MACHINE.

SPECIFICATION forming part of Letters Patent No. 580,606, dated April 13, 1897.

Application filed July 11, 1895. Serial No. 555,652. (No model.)

To all whom it may concern:

Be it known that I, WILLIS S. SHERMAN, of Milwaukee, in the county of Milwaukee and State of Wisconsin, have invented new and useful Improvements in Tongue-and-Groove Machines, of which the following is a description, reference being had to the accompanying drawings, which are a part of this specification.

10 This invention covers improvements on the machine for which Letters Patent No. 538,130 were issued to me on April 23, 1895.

15 The object of the present invention is to better the construction and increase the efficiency of the machine by improving features and details of the mechanism.

20 The invention consists of the parts and combination of parts hereinafter described and claimed, or their equivalents.

25 Figure 1 is an elevation of the left side of the machine, parts, however, being broken away and other parts being in section. Fig. 2 is a front elevation of the machine, parts being broken away and relatively disarranged for the purposes of illustration and other parts, particularly at the left of a vertical central line, being in section. Fig. 3 is a top plan of the machine, some parts, however, being omitted to better show the operative parts of 30 the machine. Fig. 4 is a front view of the tongue-cutting cutter-head. Fig. 5 is a transverse section of the tongue-cutting cutter-head on line 5 5 of Fig. 4. Fig. 6 is a transverse section of the tongue-cutting cutter-head on line 6 6 of Fig. 4. Figs. 7 and 8 are respectively front and edge views of cutters on the tongue-cutting cutter-head.

35 A is the base or frame, which is of suitable size and construction to properly support the operative parts of the machine. A driving-shaft B, a crank-shaft D, and an intermediate gear-shaft C are journaled in the frame. The driving-shaft B is provided with a pulley B', through which motion is communicated to 40 the shaft from any convenient source of power by means of a belt (not shown) running thereon.

45 The driving-shaft B is provided with a pinion K, which meshes with a spur-toothed wheel K' on the shaft C, and a pinion K² on shaft C meshes with spur-toothed wheel K³ on crank-shaft D.

The shaft D has a crank E at each end, and a pitman F connects the crank-wrists E' severally to a vertically-reciprocating slide H, 55 conveniently, by means of a stud-pin G, fixed in the slide. A cap G', secured to the end of the pin G by screw G², retains the pitman movably on the stud-pin.

In Fig. 2 the pitman F at the right is shown 60 as broken off and as being, with the crank E', to which it is attached, at the limit of its travel downwardly, while the stud-pin G above (to which this pitman is attached when in use) is, with the table H² adjacent thereto, shown 65 as being at a medial point of their travel. This relative disarrangement of parts was adopted in the drawings as permissible for showing the different positions of the tables H² in their travel.

70 The vertical edges of each slide H are preferably beveled, forming a dovetail construction in cross-section, whereby the slides are fitted, retained, and travel vertically in suitable ways therefor in upright plates I, secured to the frame A. A beveled gib I⁴, secured by holding-screws I⁵ adjustably to the plate I at one edge of each slide H, forms the bearing therefor at that edge and may be adjusted to take up wear. The rearwardly-projecting flange or tongue I⁷ of the T-formed plates I are provided with horizontally-disposed elongated slots, through which bolts I⁸ pass and turn into the frame, whereby the plates are secured adjustably to the frame. 75 The plates are adjustable toward and from each other laterally by means of the reversely-threaded screw U, turning through the ears I⁶ on the tongues I⁷. Horizontally-disposed ribs I² on the tongues I⁷ enter grooves therefor in the frame A and support the plates adjustably thereon.

80 A horizontally-disposed shelf or table H² is secured to the side of each slide H conveniently by means of screws H³ through a vertically-disposed flange of the table, turning into the slide H. The tables H² are the supports on which a board or strip of flooring is rested and on which it is carried upwardly past and thereby fed to the cutters herein- 85 after described.

90 Near to and just in front of the cutters at each side of the machine the upright plate I has a vertical face I', adapted to receive 100

against it and support the board movably at one side edgewise. Directly opposite this bearing-surface I' and complementary thereto at a little distance therefrom is a yielding 5 presser-bar J, adapted to hold the board with sufficient force, but yieldingly, up to the bearing-surface I'. These presser-bars J are severally of such length vertically that they extend to a distance above and below the cutters and at each end are secured to the plate I by stud-bolts S, fixed in the plate I, which 10 bolts pass loosely through the bar J and are provided with sets of nuts S' and S'', the nuts S'' being on the inside to limit the movement 15 adjustably of the bar toward the bearing-surface I' and the nuts S' being outside the bar at a distance therefrom to adjust the compression of springs S², interposed between them and the bar, and also to limit the movement 20 of the bar outwardly away from the bearing-surface I'. The bars J are severally provided with a smooth and substantially vertical bearing-surface J² in front of the cutters and opposite the bearing-surface I' on the plates I. 25 This bearing-surface J² terminates at a point a little above and a little below where the strip is acted on by the cutters, and the face of the bar J above and below the surface J² is cut away somewhat, so as to provide greater 30 space between the bar and the plate that the board or strip may be readily inserted below and withdrawn after it has been carried up past the cutters. A forwardly-projecting beveled part J', Fig. 3, on each of the bars J 35 serves as a guide for directing the entrance of the board or strip between the bar and the plate.

In practice the bar J is first adjusted so as to be parallel with the plate I, at such distance therefrom that the surface J² is as far away from the surface I' as equals the thickness of the material Z, and the upper nuts S'' are then moved inwardly a little on the pins S, so that the surfaces I' and J² will, by 40 reason of the then slight inward tilt of the bar, be a little nearer each other than equals the thickness of the material, whereby, when the material is forced up between them, the material or strip will be held firmly against the 45 surface of the plate I, thereby, notwithstanding slight differences of thickness of boards or strips, holding the smooth or top surface of the board truly and firmly against the surface I', thus providing for cutting a tongue 50 or groove at a regular and predetermined distance from the top surface of the board. It must also be understood that in practice the springs S² at the respective ends of the bar J are of equal strength, and as the bearing-surface J² is preferably nearer one end 55 of the bar than the other end when the material is forced upwardly between this surface J² and the plate I that normally only the upper end of the bar J will swing away from the plate I, the loose connection at the other end of the bar serving merely as a hinge to permit such movement.

It will be seen that the vertically-moving slides H, with their tables H² and related mechanisms, are in duplicate, one set at each 70 side of the machine, and it must be understood that at one side of the machine the board or strip is pushed into the machine over the table H² and is fed by the vertically-moving slide H to tongue-cutting cutters, and 75 at the other side the other end of the board or strip is similarly fed to a groove-cutting cutter.

For cutting the groove in one end of the material or strip I employ a suitable circular 80 saw V. This saw is fixed on an arbor O conveniently by being put on the arbor against a boss or collar P and being held thereto by the loose ring-collar P², secured in place by the nut O³ turning on the arbor. The arbor 85 O is journaled in boxes M, fixed on or integral with the bed-piece R, which piece is fitted on a dovetailed member A' of the frame A. The bed-piece R is adjustably and detachably secured on the dovetailed member 90 A' by the holding-screws N turning through the bed-piece against a gib or bearing-piece N⁴, interposed between the bed-piece and the member A'. The saw or grooving-cutter V is located directly in rear of a table H² and 95 opposite the space between a plate I and a bar J, the exact distance of the saw from the plane of the bearing-surface I' being secured by adjustment of the screw U, that is adapted to move the plate I laterally. A stop L², 100 secured on the member A' below the saw V, receives the strip or material against it and thus limits the depth of the groove to be cut in the strip. The depth of this groove is regulated by adjustment of the position of the 105 bed-piece R by means of the screw N³, that turns into the bed-piece and bears against a rib A⁶ on the member A'. The saw V can be removed for sharpening or to be replaced by another saw readily by releasing the 110 screws N, sliding the bed-piece R rearwardly away from the stop-block L, and removing the nut O³ and collar P². The arbor O is provided with a pulley Q for communicating motion thereto by a belt from any convenient 115 source of power. For cutting the tongue on the other end of the board or strip I employ cutters mounted on revolving cutter-heads W W opposite each other. The heads W W are mounted detachably one on each of the 120 arbors O', which are journaled parallel to each other in boxes M' M' on the two bed-pieces R' R', adjustably fitted on the dovetailed member A² of the frame A, and are held releasably thereto by the screws N' N', 125 advisably turning against an interposed gib-piece. The positions of the bed-pieces R' R' relative to each other and to the bearing-surface I' of the plate I are regulated laterally by the screws N² N², severally turning into a 130 bed-piece R' and bearing against the rib A⁷ on the member A². The arbors O' are provided with pulleys Q' for driving them.

The heads W W are each provided with two

sets of cutters duplicate of and complementary to each other on the two heads. One set of cutters is composed of the oppositely-disposed flat blades Y Y, each having a saw-toothed arc edge projecting slightly beyond the perimeter of the head W. These blades or parting-cutters Y Y are fitted in suitable recesses or a diametrical channel across the surface of the head and are held adjustably thereto by 10 countersunk bolts Y², passing through radially-elongated slots W' in the head and secured thereto by nuts Y³, turning on the bolts against the heads. These cutters Y Y are adapted to cut across and part the grain of 15 the material or strip in advance of the clearing or tongue-forming cutters, thus forming the shoulder or relish on the strip or board.

The other set of cutters, being the material-removing or tongue-forming cutters X X, consist of stocks, preferably of disk form, a portion of which at the circumference is removed, forming tangential projections having knife-edges adapted to cut circumferentially. These disks or cutters are secured to the head 20 by countersunk bolts X², provided with nuts X³, and are so disposed on the heads that the knife-edges project beyond the perimeter of the head, whereby they are adapted to cut into and remove portions of the material held thereto as the head revolves. These heads are secured to their arbors O' O' conveniently by turning them by screw-thread onto the sleeves P' P', which are shrunk onto the arbors. The heads W W are so disposed relative to a plate I that the strip or material bearing against the surface I' and shoved past the bar J is in the vertical plane between the cutter-heads W W. The heads W W can be readily removed from their arbors O' O' for 25 sharpening the cutters or for replacing them with others by releasing the screws N' and sliding the bed-pieces R' R' severally laterally on the member A² sufficiently far that the heads can be unscrewed from the sleeves P' without contacting with other parts of the machine normally in front of them. A stop 30 L, secured adjustably by screws L' L' on the member A², is adapted to receive the end of the strip and regulate and determine the 35 length of the tongue to be cut on the strip.

As it is desirable that there shall be a slight undercut of the strip at one end from the surface that is to form its outer face, the arbors O' O' are advisedly disposed at a slightly-oblique angle to the plane of the bearing-face I' of the plate I adjacent thereto, and to secure this position of the arbors the dovetail bearing-surfaces of the member A² are longitudinally correspondingly oblique transversely to the plane of the bearing-surface of the plate I. As this undercut is very slight the obliquity of the longitudinal direction of the dovetailed surfaces therefor is not shown in the drawings, as it is too slight to be illustrated in drawings of the scale of those here-with.

In practical operation the attendant, rest-

ing one end of a strip, as of flooring, on the table H², pushes it between a plate I and the adjacent bar J against the stop L, when the 70 table is going down or is at its lowest limit of travel, and holds it there while the table goes up, actuated by a pitman F, and as it goes up between the bearing-surfaces I' and J² and passes the saw or the cutters a groove 75 or a tongue is cut in or on the strip, and thereupon the strip being raised above the bearing-face J² of the bar J is readily withdrawn and the other end of the strip is similarly presented to the cutter or cutters at the 80 other side of the machine and the complementary groove or tongue is similarly formed.

Having thus described my invention, what I claim, and desire to secure by Letters Patent, is—

1. In a tongue-and-groove or analogous machine, the combination with a reciprocating material-supporting table, of a stationary material-supporting plate, and a yielding material-supporting bar opposite thereto, substantially as described.

2. In a tongue-and-groove or analogous machine, the combination with the frame, of an elongated stationary material-supporting plate, an elongated yielding material-supporting bar opposite to and extending in the same direction with the plate and movable from and toward the plate in a plane at a right angle to the surface thereof, and a material-supporting table reciprocable in the 100 space between said plate and said bar, substantially as described.

3. In a machine of the character described, the combination of a stationary material-supporting plate having an elongated bearing-surface to receive thereagainst and support the material, an elongated yielding material-supporting bar extending in the same direction and opposite the bearing-surface of the material-supporting plate and yielding from 105 and pressing toward the plate at a right angle thereto, studs fixed in the plate projecting therefrom through the bar in and at right angles to the plane of the extension of the path of the material and on which the bar moves 110 toward and from the plate, and a material-supporting table reciprocable alongside of the plate and in the space between the plate and the yielding bar, substantially as described.

4. In a tongue-and-groove or analogous machine, the combination with a single reciprocating material-supporting table, of a stationary material-supporting plate elongated in the direction of the motion of the material-supporting table, a bar opposite the stationary material-supporting plate, studs fixed in the plate extending through the bar on which the bar near its extremities is movable at a right angle thereto toward and from the plate, springs holding the bar yieldingly toward the 125 plate, and nuts on the studs limiting the movement of the bar toward the plate and holding the springs against the bar, the table being so disposed as to reciprocate in the 130

space between the bar and the plate, substantially as described.

5. In a tongue-and-groove machine, the combination with the frame, of a stationary material-supporting plate having an elongated bearing-surface and ways therein parallel with said bearing-surface for a movable table, means substantially as described for securing said plate adjustably on the frame, a material-
10 supporting table reciprocable on the ways in said plate, and means for reciprocating said table.

6. The combination with the frame, of bed-pieces R'R' adjustable on the frame, parallel arbors carrying complementary cutter-heads mounted on the bed-pieces, an intermediate stop or rib A⁷ on the frame, and regulating screws interposed between the bed-pieces and the stop, substantially as described.

15 7. In a tongue-and-groove or analogous machine, the combination with the frame, of reciprocating material-supporting tables, substantially duplicate material-supporting plates secured adjustably but otherwise non-movably to the frame and having therein the bearings of said reciprocating tables, and a reversely-threaded screw turning into adjacent parts of the plates and adapted to adjust the plates toward or from each other, either
25 30 by moving both plates on the frame or by moving one plate only, as set forth.

8. The combination with the frame, and two vertically-reciprocating material-supporting tables actuated by a common shaft, of corresponding sets of non-reciprocable devices adapted to support the material in position while it is being fed to cutters on and with the movement of the tables, and cutters or sets of cutters at the rear of each set of material-supporting devices, substantially as described.

9. The combination with the frame, of a vertically-disposed non-reciprocating material-supporting plate and complementary bar opposite thereto, a material-supporting table reciprocable vertically in the space between the plate and complementary bar, opposite and complementary cutter-heads at the rear of the material-supporting plate and bar, and
45 50 a stop to receive the end of material and regu-

late the extent of the material presented to the cutters, substantially as described.

10. In a tongue-and-groove machine, the combination with the frame, of a plate having a material-supporting bearing-surface, 55 and a bar opposite thereto yielding therefrom and pressing thereto at a right angle to the plate having a bearing-surface nearer to one end thereof than to the other end, and means substantially as described securing the bar at points in the extension of the plane of the path of the material and adjacent to the plate yielding so that the material for which the machine is adapted being forced between its bearing-surfaces and the plate will cause it 60 to yield at that end nearest to the bearing-surface only.

11. In a tongue-and-groove machine, the combination with a fixed plate having a longitudinal material-supporting bearing-surface, 70 of a pressure-bar held yielding near to opposite and substantially parallel with the longitudinal bearing-surface on said plate, and an inclined guide on the bar projecting laterally from the bar opposite the plate 75 adapted to receive and guide the end of the material being thrust endwise into the space between the plate and the pressure-bar, substantially as described.

12. The combination of an elongated material-supporting plate having a straight longitudinal bearing-surface, studs fixed in the plate one near each end thereof and projecting therefrom in the line and on the side of the bearing-surface, a complementary material-supporting bar having a flat bearing-surface nearer one end of the bar than the other but opposite the bearing-surface on the plate, said bar being movable on said studs toward and from the plate, at a right angle 85 thereto and means to retain the bar yielding adjacently to the plate, substantially as described.

In testimony whereof I affix my signature in presence of two witnesses.
